UNITED STATES PATENT OFFICE.

ROBERT L. WHITSEL, OF SOUTH CHICAGO, ILLINOIS.

CIGAR AND CIGARETTE HOLDER.

Application filed June 26, 1926, Serial No. 118,645. Renewed August 6, 1928.

This invention relates to holders for cigars and cigarettes and aims to provide an article of this character that is so constructed as to afford not only a holder for the cigar or cigarettes, but also a receiver for the ashes dropped therefrom so that the same will not fall upon the floor when the holder is being held in the hand or upon the desk, table, or other support when the holder within which the cigar or cigarette is arranged is disposed thereon.

The invention further aims to provide a holder of the foregoing type that is additionally so constructed as to enable the same to be disposed upon a desk or table without any liability of the cigarette burning or otherwise marring the surface of the desk or support, and without any liability of the holder rolling from place to place, while resting upon the desk.

Other objects will become apparent as the nature of the invention will be better understood, the same comprising the novel form, combination, and arrangement of parts, hereinafter more fully described, shown in the accompanying drawing and claimed.

In the drawing wherein like reference characters indicate corresponding parts throughout the various views:

Figure 1 is a top plan view of my improved cigar and cigarette holder.

Figure 2 is a side elevation thereof, and

Figure 3 is an enlarged longitudinal fragmentary section disclosing more clearly the cigarette receiving and stem attaching nipple of the holder.

Now having particular reference to the drawing, my novel holder constitutes the provision of an open top receptacle 5 of a length slightly greater than the length of the brand of the cigar or cigarette preferred by the smoker and of a width slightly greater than the cross sectional area of said cigar or cigarette as clearly disclosed in Figure 1. The upper edges of the side walls of the receptacle 5 are flared outwardly to assume the formation of wings 6—6 for facilitating the disposition of a cigarette or cigar therein. The back wall of the receptacle 5 extends upwardly to the edge of the wings, whereas the front wall terminates at the lower edge of the wings so as to permit the cigar or cigarette to be engaged or removed from the receptacle by the passage through the wings at the front end thereof.

The rear wall of the receptacle 5 at the upper edge thereof is formed with a threaded opening 7 within which is arranged the intermediate threaded portion of a horizontally arranged nipple 8. The inner or forward end of this nipple is enlarged and socketed as at 9 for receiving the proper end of the cigar or cigarette as clearly indicated in Figure 1. The opposite end of this nipple that is exteriorly of the receptacle 5 is formed with a horizontal threaded socket 10 for receiving the inner threaded end of a preferred type of stem 11, said nipple being formed with a longitudinal smoke passage 12 in communication at its opposite ends with said cigarette socket 9 and stem within the threaded socket 10.

It will thus be seen that when the cigar or cigarette is arranged within the socket 9 the ashes falling therefrom will be entirely caught within the receptacle 5 and thus prevent the dropping of the same upon the floor or upon a desk, table, or the like, if disposed thereon. It will also be seen that due to the provision of the receptacle 5 the holder may be readily arranged upon a support without any liability of the same moving accidentally from place to place and causing the cigarette to drop therefrom. Also, in view of the provision of the receptacle there will be absolutely no liability whatever of the lighted end of the cigarette coming in contact with a support for marring the same.

Even though I have herein shown and described the invention as consisting of certain detail structural elements, it is nevertheless to be understood that some departures may be had therefrom without affecting the scope of the appended claim.

Having thus described the invention, what I claim as new and desire to secure by Letters Patent is:—

In a cigar and cigarette holder of the class described, a substantially rectangular shaped open top receptacle, the side walls thereof being flared outwardly at their upper ends to provide wings, the upper edge of the forward end wall of the receptacle terminating at the lower edges of the wings, the upper edge of the rear end wall of the receptacle extending to the upper edges of the wings, the upper portion of the rear end wall being provided with a threaded opening, a nipple extending through the opening, the intermediate portion thereof being threaded for engagement with the threaded opening, an enlarged

socket member formed on the forward end of the nipple for receiving one end of the cigar or cigarette and disposed between the rear end portions of said wings, the rear face of the enlarged socket member engaging the inner face of the upper portion of the rear end wall of the receptacle, the other end of the

nipple being provided with a stem receiving socket, said nipple being further provided with a longitudinal smoke passage affording communication between the respective sockets.

In testimony whereof I affix my signature.

ROBERT L. WHITSEL.
